TUBE CLOSURE

Gunnar F. Seashore, Minneapolis, Minn.

Application October 31, 1935, Serial No. 47,594

11 Claims. (CL 221—60)

My present invention provides an extremely simple and highly efficient closure for receptacles such as collapsible tubes for containing semi-fluid materials, such for example, as tooth paste or shaving cream. The novelty resides chiefly in the discharge neck of the tube or receptacle and the co-operating closure cap, whereby important advantages, hereinafter set forth are attained.

10 A commercial form of the invention is illustrated in the accompanying drawings wherein like characters indicate like parts throughout the several views.

Referring to the drawings:

15 Fig. 1 is an enlarged view in elevation with parts broken away showing the invention applied to a collapsible tube such as above noted;

Fig. 2 is a fragmentary section taken on the line 2—2 of Fig. 1;

20 Fig. 3 is a view corresponding to Fig. 2 but illustrating different positions of the parts;

Fig. 4 is a section taken on the line 4—4 of Fig. 2;

25 Fig. 5 is a section taken on the line 5—5 of Fig. 2;

Fig. 6 is a plan view of the parts shown in Fig. 1, some portions being broken away; and

Fig. 7 is a view corresponding to Fig. 6 but illustrating a slightly modified form of the cap.

30 The collapsible tube 8 is formed with the customary relatively rigid conical crown end 9 that terminates in an externally threaded discharge neck 10. As an important feature of the invention the neck is provided with a disk-like valve head 11 that is formed integrally with and offset axially above the extreme end of said neck so as to afford a substantially annular discharge 35 passage 12. This valve head 11 is formed integral with the neck 10, being rigidly connected thereto by a plurality of radial ribs or webs 13. The said neck structure and valve head are, in practice, integrally formed by being stamped or pressed from a piece of pliable metal, such as lead or some of the comparatively soft lead alloys, from which also the crown portion 9 is adapted 40 to be formed by a single operation. The punch of the die will simultaneously form the neck passage, the ribs 13 and the valve head 11. In fact, the valve head is formed by a portion punched out to form the passage through the neck 10, and hence, is of the same diameter as the passage in said neck. The discharge passage 12 is therefore formed by the offsetting of the valve head 11 from the extreme end of the neck.

55 Working with threaded engagement on the

neck 10 is a cap 14, the outer end of which is inwardly flanged to form a valve seating surface 15 through which opens the final discharge passage 16. The discharge passage 16 may take various forms but in any event will be of less area than the valve head 11 so that when the cap is screwed down on the neck, the upper peripheral edge of said valve head will be seated against the valve seating surface 15.

Here it is important to note that when the 10 cap is screwed down to close the tube, as shown in Fig. 2, there will be no flat or extended contact between the valve head and valve seat but the former will engage the latter only at its upper

edge and with substantially a circular line contact. This will cut off the discharge of the contents from the tube without caging any of the paste or tube contents between contacting surfaces. It has been found in practice that where a cap and a valve structure engage each other with an extended flatwise contact, paste will be caged between the contacting surfaces preventing a sharp cut off of the discharge and leaving lodged between the surfaces substance which, when dried, frequently causes the cap and neck 15 structure to be stuck together making opening difficult. Moreover, with the applicant's improved closure structure the cut off of the discharge of the paste is very close to the final discharge passage and to the extreme outer portion of the cap 20 which prevents accumulation of paste outward of the valve head.

Fig. 7 is a view corresponding to Fig. 6 but illustrating a slightly modified form of the cap. 25

The said neck structure and valve head are, in practice, integrally formed by being stamped or pressed from a piece of pliable metal, such as lead or some of the comparatively soft lead alloys, from which also the crown portion 9 is adapted to be formed by a single operation. The punch of the die will simultaneously form the neck passage, the ribs 13 and the valve head 11. In fact, the valve head is formed by a portion punched out to form the passage through the neck 10, and hence, is of the same diameter as the passage in said neck. The discharge passage 12 is therefore formed by the offsetting of the valve head 11 from the extreme end of the neck.

Working with threaded engagement on the 30 neck 10 is a cap 14, the outer end of which is inwardly flanged to form a valve seating surface 15 through which opens the final discharge passage 16. The discharge passage 16 may take various forms but in any event will be of less area than the valve head 11 so that when the cap is screwed down on the neck, the upper peripheral edge of said valve head will be seated against the valve seating surface 15.

Here it is important to note that when the 35 cap is screwed down to close the tube, as shown in Fig. 2, there will be no flat or extended contact between the valve head and valve seat but the former will engage the latter only at its upper edge and with substantially a circular line contact. This will cut off the discharge of the contents from the tube without caging any of the paste or tube contents between contacting surfaces. It has been found in practice that where a cap and a valve structure engage each other with an extended flatwise contact, paste will be caged between the contacting surfaces preventing a sharp cut off of the discharge and leaving lodged between the surfaces substance which, when dried, frequently causes the cap and neck 40 structure to be stuck together making opening difficult. Moreover, with the applicant's improved closure structure the cut off of the discharge of the paste is very close to the final discharge passage and to the extreme outer portion of the cap 30 which prevents accumulation of paste outward of the valve head.

As a further important feature the cap 14 is provided with a skirt-like flange 17 that extends outward of or substantially flush with the exterior of the tube. In the present instance the crown of the tube being conical, the flange 17 is also made conical to closely follow the crown. Preferably, the perimeter of the flange 17 is knurled and the knurled portion is slightly projected beyond the diameter of the tube so that it may be more readily engaged by the thumb and fingers of a hand, as shown in Fig. 1, by reference to which it will be observed that the tube can be conveniently held in one hand and the cap operated to open and close the tube manipulated by the fingers of the same hand. This is a decided advantage because it leaves the operator's other hand free for manipulation of a tooth brush or the like.

In the preferred arrangement the cap 14 is so proportioned that its valve seating surface 15 will seat against and make seating contact with the upper peripheral edge of the valve head 11 while the flange 17 is still slightly spaced from 45

the valve head 11 so that when the cap is screwed down on the neck, the upper peripheral edge of the valve head 11 will be seated against the valve seating surface 15.

Working with threaded engagement on the 50 neck 10 is a cap 14, the outer end of which is inwardly flanged to form a valve seating surface 15 through which opens the final discharge passage 16. The discharge passage 16 may take various forms but in any event will be of less area than the valve head 11 so that when the cap is screwed down on the neck, the upper peripheral edge of said valve head will be seated against the valve seating surface 15.

Here it is important to note that when the 55 cap is screwed down to close the tube, as shown in Fig. 2, there will be no flat or extended contact between the valve head and valve seat but the former will engage the latter only at its upper edge and with substantially a circular line contact. This will cut off the discharge of the contents from the tube without caging any of the paste or tube contents between contacting surfaces. It has been found in practice that where a cap and a valve structure engage each other with an extended flatwise contact, paste will be caged between the contacting surfaces preventing a sharp cut off of the discharge and leaving lodged between the surfaces substance which, when dried, frequently causes the cap and neck 60 structure to be stuck together making opening difficult. Moreover, with the applicant's improved closure structure the cut off of the discharge of the paste is very close to the final discharge passage and to the extreme outer portion of the cap which prevents accumulation of paste outward of the valve head.

the conical crown of the tube and the cap 14 is made of semi-flexible or yielding material which will yield sufficiently after engagement of the said valve-forming surfaces to permit such slight further movement of the cap as is necessary to bring the flange 17 thereof into surface engagement with the conical crown of the tube. This sealing engagement of the cap and tube below the screw-threads is important since it prevents leakage through the threads in case pressure is applied to the tube contents while the upper valve surfaces are sealed. The cap may be made of any kind of material having the desired resilient or yielding characteristics, but hard rubber has proven satisfactory for the purpose. If, however, the cap is formed of material not having the desired resilient or yielding characteristics the use of a suitable gasket between the cap and flange of the valve head is recommended.

20 In the structure just considered, see particularly Fig. 6, the final discharge opening 16 in the cap is round but in the arrangement shown in Fig. 7, the final discharge passage 16a of the cap is in the form of an elongated passage or slot.

25 In practice it has been found that the improved closure structure described may be made at a very small cost and that the entire neck structure, including the neck 10, crown 9, valve head 11, and ribs 13, may be formed by one stamping operation produced by properly constructed dies. The threading of the exterior of the neck 10 and of the interior of the cap 14 will usually be produced by separate operations.

30 From the foregoing, it will be understood that the invention described is capable of modification as to details of construction and arrangement of parts within the scope of the invention herein disclosed and claimed.

What I claim is:

40 1. A container having a discharge neck provided with an axially located disk-like head spaced axially therefrom to afford a discharge passage, said head having a relatively sharp valve-acting annular edge, and a valve-acting cap applied to said neck for axial movements in respect thereto and having an axial discharge passage outward of and of less diameter than the said disk-like head, said cap having an annular valve-acting surface surrounding the discharge 50 passage therein, the said annular valve-acting surface of the cap having, when the parts are drawn axially together, complete flat surface to sharp edge contact with the valve-acting edge of the disk-like valve head, but being spaced from the valve head except at the place of flat surface to sharp edge contact.

55 2. The structure defined in claim 1 in which said valve head is located entirely outward of said neck and has the same diameter as the passage in said neck, and circumferentially spaced ribs connecting said valve head to said neck, said ribs being integrally formed with the neck and valve head.

3. The structure defined in claim 1 in which said cap is formed with a skirt flange terminating approximately at the exterior of said container.

4. A container having a discharge neck provided with a disk-like valve head spaced therefrom and projected outward thereof to afford a discharge passage, and a cap having threaded

engagement on said neck and provided with an inwardly projected valve seating flange overlapping said valve head, the outer perimeter of said head having an annular edge, the said annular edge of the valve head being arranged to engage and make annular line sealing contact with the valve seating flange at a point closely adjacent the final discharge passage formed by said flange, said annular edge being the only point of contact of the head with the valve seating flange of the cap, other parts of the head being spaced from the cap flange when the edge and flange are in sealing contact.

5 5. The structure defined in claim 2 in which said valve head is located entirely outward of said neck and is of the same diameter as the passage of said neck.

6. The structure defined in claim 2 in which said valve head is located entirely outward of said neck and is of the same diameter as the passage of said neck, and circumferentially spaced ribs connecting said valve head to said neck, said ribs being integrally formed with the neck and valve head.

7. The structure defined in claim 4 in which said cap is formed with a skirt flange terminating approximately at the exterior of said container.

8. A cylindrical container having a conical end portion provided with an axial discharge neck of reduced diameter, a valve-acting cap screw-threaded onto the discharge neck, said cap having a substantially axial discharge passage, said cap and neck having co-operating valve surfaces adapted to be brought into sealing engagement under screw-thread action of the cap in respect to the neck to close the container, and said cap being formed with a skirt flange terminating approximately at the cylindrical exterior of the container.

9. The structure defined in claim 8 in which the said skirt flange of the cap is conical to conform to the conical end portion of the container and terminates approximately at the cylindrical wall of the container.

10. The structure defined in claim 8 in which the said skirt flange of the cap is conical to conform to the conical end portion of the container and terminates approximately at the cylindrical wall of the container, said cap, neck and cap flange being so proportioned that the conical surfaces of the cap flange and container will be brought into sealing engagement just after sealing engagement is accomplished between the said cooperating valve surfaces.

11. The structure defined in claim 8 in which the said skirt flange of the cap is conical to conform to the conical end portion of the container and terminates approximately at the cylindrical wall of the container, said cap, neck and cap flange being so proportioned that the conical surfaces of the cap flange and container will be brought into sealing engagement just after sealing engagement is accomplished between the said cooperating valve surfaces, and said cap being formed of sufficiently resilient material to permit engagement of the conical cap flange with the conical surface of the container after the cooperating valve surfaces have been brought into sealing engagement.

GUNNAR F. SEASHORE.
